Attn:

UNITED STATES PATENT OFFICE.

FREDERICK A. TRINKLE, OF HARVEY, ILLINOIS.

POWER PLANT.

Application filed December 20, 1924. Serial No. 757,226.

This invention relates to power plants, and more particularly to steam generating systems for use in vehicles although it may be used with equal advantage for other purposes.

It contemplates more especially the provision of means constituting individual steam generating units arranged within a combustion chamber so as to expose a maximum radiating or absorbing surface to the hot combustion gases issuing from the burner element.

Further, the generating units, in this instance a series of individual spirally arranged spaced coils, are interconnected so as to create a uniform pressure throughout the system, and also to effect the withdrawal of moisture or condensate from the generating units.

One object of the present invention is to improve the construction and operation of devices of the character mentioned.

Another object is the provision of a more efficient, and less complicated device of the above mentioned type. This is accomplished in the present embodiment by providing unusually large heat absorbing surfaces to completely utilize practically all of the heat inherent in the products of combustion prior to their escape from the combustion chamber.

A further object is to provide a compact, durable, and efficient power plant.

It is also an object of this invention to provide in a plant of this kind a watertube boiler which has a maximum of steam storage for the provision of reserve steam.

Other objects and advantages will appear from the following description of an illustrated embodiment of the present invention.

On the drawings:

Figure I is an assembled view of the installation embodying this invention.

Figure II is a detail view partly in section of the gasoline valve and actuating mechanism therefor.

Figure III is a plan view of a part of the installation shown in Figure I.

Figure IV is a sectional view of the boiler taken at the line 4—4 of Figure V and showing parts in elevation and parts omitted.

Figure V is a cross sectional view along the line 5—5 of Figure IV, with parts shown in elevation.

Figure VI is a cross sectional view of part of the automatic control mechanism.

Figure VII is a detached plan view of the fire box with the burner connected thereto.

Figure VIII is an elevational view partly in section of Figure VII.

Figure IX is a diagrammatic sketch showing the wiring of the control mechanism.

As shown on the drawings:

The boiler selected for illustration comprises a casing 1 preferably of circular cross section, which is provided with a suitable opening at the top thereof to receive a horizontally disposed water supply pipe 2. A preheater coil 3, in this instance a pipe defining a spiral, occupies the uppermost portion of the casing and is in communication with the water supply pipe 2. As shown, the pipe 3 terminates in a vertically disposed pipe which projects downwardly through the top of a cylindrical header 4 supported within the casing near the wall thereof in any appropriate manner, so as to discharge the initially heated water near the bottom for said header 4.

A series of spirally arranged generating coils 5 each having a plurality of convolutions in a common plane, are spaced within the casing 1 in superposed relation and constitute baffle means. The several coils 5 are in connection at their outer ends with the header 4 at the vertically spaced points in the length of said header. The other end or inner extremity of each coil 5 communicates with a header 6 vertically disposed within the casing, in this instance, in proximity to the header 4, which header 6 is longitudinally apertured as at 6^a to receive and establish communication with the radial connection 5^a of each of the coils so as to serve as inter communicating means for the coils 5. Thus it will be apparent that the generating pressure is uniformly maintained throughout the generating system by reason of the headers 4 and 6, and that the presence of excess moisture and condensates is avoided by permitting the latter to be discharged to the headers whereupon it is returned to the lowermost coil which is in proximity to the burner thereby tending to produce steam of high quality.

A pipe 7 which leads to the steam control mechanism, is secured in any suitable manner to the upper extremity of the header 6 and branches into a pipe 8 which depends along the outside of the generating coils 5 and is connected to the storage coil 9 helically arranged within the casing exterior to

and surrounding the generating coils 5 in spaced relation. It is to be noted that the pipe 8 extends downwardly to the lowermost portion of the helically rising storage 6 coil 9, whereas the upper extremity of said coil 9 communicates with a vertically disposed pipe 10 which also depends outside of the generating coils and is connected to a spiral superheating coil 11 similar to one of 10 the generating coils and terminating at its center at 12 to enter the engine through suitable valves.

With the arrangement of parts above described it will be apparent that a compact, 15 durable steam, and efficient generating plant has been provided which is adapted to withstand excessive pressures largely owing to the fact that a uniform pressure is maintained throughout the generating system, 20 since each generating coil is in communication with the headers 4 and 6 which serve as pressure equalizers.

A cover plate 13 is secured in any suitable manner to the top of the casing 1, and is centrally apertured to communicate with a flue 14 which leads to the atmosphere. The member 14 is provided with an opening centrally located with respect to the casing 1, which is in communication with the central opening 25 of the plate 13. A circular closure plate 15 is associated with the stack 14 to cover the opening provided therein. A plurality of bolts 17 extend through appropriate openings spaced about the periphery of the plate 30 15, and are anchored in the cover plate 13. A helical spring 16 is associated with the shank of each bolt 17 intermediate the extremity thereof and the closure 15, so that when the pressure becomes excessive and 35 reaches a predetermined value, the plate 15 will be raised against the action of the spring 16 thereby relieving the pressure. The nuts of the bolts 17 may be adjusted to vary the tension in the spring so as to control the release of the pressure at any predetermined 40 value.

A fire box 18, preferably of circular cross section, is secured to the lower edge of the casing 1 in any appropriate manner. The interior of the fire box 18 is provided with a lobe formed integral with the interior thereof of diametrically opposite the fuel feeding mechanism, so as to impart a twirl to the fuel in order to assist in completely atomizing the 45 fuel and insuring complete combustion thereof.

The burner mechanism.

The burner (Figure VIII) comprises a 50 cylindrical member 19 secured in and communicating with the interior of the fire box 18 at a point opposite to the above mentioned heart shaped portion of said fire box. The outer portion of said cylindrical member 19 55 communicates with and is secured in a cast-

ing 20 which is shaped to provide a nozzle 21, a chamber 22 and an aperture 23 communicating between said chamber and nozzle. The exterior wall forming the inner portion of chamber 22 and the nozzle 21 is cylindrically shaped and is in axial alignment with and extends part way into the cylindrical member 19. A closure member 24 closes the exterior of the chamber 22 and has adjustably secured therein a hollow tube member 25 the inner end of which is partially closed to constrain the flow of oil therethrough to a fine stream. The outer end of the tube 25 communicates with a fuel supply valve 26 which is secured in the closure member 24 and adapted to be adjusted to vary the flow of oil to the tube 25. A pipe 27 communicates with valve 26 for supplying fuel thereto. A pipe 28 communicates with the chamber 22 for supplying steam thereto. A tube 29 is secured to, and communicates with, the interior of casting 20. The tube 29 is similar in shape to tube 25 and extends inwardly to a point adjacent the nozzle 21. The tube 29 communicates with a pipe 30 for supplying gasoline thereto. The casting 20 has also secured thereto a blower 31 which also communicates with the interior of said casting. 70 75 80 85 90 95

Extending into the cylindrical member 19 adjacent the nozzle 21 and the mouth of tube 29 are a pair of spark plugs 32. The spark plugs 32 are electrically connected to a suitable spark coil 33.

The gasoline valve.

By referring to Figure II there will be seen the valve and mechanism for controlling the supply of gasoline to the burner via the pipe 30.

Supported on a housing 34 of the gasoline 105 valve is a solenoid 35 which when energized is adapted to rock an arm 36 about a pivot 37 on a bracket 38 integral with a housing 39 secured to the housing 34, and hold said arm 36 in rocked position. The housing 39 is apertured to receive a guide member 40 in which is slidably a stem 41 suitably secured at one end to one end of the arm 36 and rigidly secured at the other end to a bearing member 42. Said bearing member 42 is rigidly secured to a diaphragm 43 clamped between the housing 39 and the housing 34. A second bearing member 44 is slidably secured on the stem 41 beneath the guide member 40. A spring 45 surrounding the stem 41 and adapted to hold the bearing members 42 and 44 apart acts to hold the diaphragm 43 in flat position. The upper portion of the housing 34 is recessed to receive a valve stem 46 having a flanged head thereon by means of which 110 a spring 47 surrounding said stem and acting, against the bottom of the recess is adapted to impel the stem upwardly against the diaphragm 43. The bottom of the stem 46 is shaped to form a valve 48 which when drawn 115 120 125 130

upward from its seat 49 due to the energization of the solenoid 35 is adapted to permit gasolene to be admitted from the pipe 50 connected beneath the valve to the pipe 30 connected thereabove. The pipe 50 leads from the gasolene tank while the pipe 30 is connected to the burner.

Automatic steam valve.

10 The pipe 7 previously referred to in connection with the boiler (Figure IV) has secured thereto above the boiler casing 1 a T-member 51 (Figure VI) with which it communicates. Rigidly secured to the T-member 51 and communicating therewith are additional T-members 52 and 53. Integral with member 53 is a valve housing 54 which embraces a valve and valve stem 55 therein. Said valve and stem 55 being adapted to be manipulated by a handle thereon for admitting steam from the pipe 7 to a by-pass 57 suitably connected to the housing 54 and communicating therewith above a valve seat 58 of the valve 55. Pipe 59 is rigidly secured to the T-member 53 and communicates therewith. The other end of the pipe 59 is connected to the water regulator which may be of any suitable type for regulating the supply of water to the boiler in accordance with 30 the steam pressure. The pipe 60 is rigidly secured to the T-member 52 and communicates with the interior thereof. The other end of the pipe 60 is connected to a suitable steam gauge for indicating the steam pressure in the boiler. The member 52 is also rigidly secured to a plate member 61 and communicates with an aperture 62 extending through said member 61. A diaphragm 63 is clamped between said plate member 61 and a housing 64. In the end of the housing 64 opposite to the member 61 and aligned with the aperture 62 in said member is a guide member 65. The guide member 65 has slidably therethrough, a stem 66. Slidably secured on the stem 66 beneath the guide member 65 is a bearing member 67 which is adapted to be abutted by a spring 68 secured around said stem. Rigidly secured to one end of the stem 66 is a second bearing member 69. Said bearing member 69 is adapted to abut the diaphragm 63 and be actuated thereby in accordance with the pressure on the other side of said diaphragm.

Axially aligned with the housing 64 and secured on a common support 70 therewith is a housing 71 which is apertured to receive the other end of the stem 66. The housing 71 has secured thereto a housing 72. Clamped between the two housings 71 and 72 is a diaphragm 73. Within the housing 72 is a valve and stem 74, said stem having a rounded head thereon. The diaphragm 73 is preferably shaped to conform to the curvature of the head of the stem 74 and the housing 71 recessed therefor. The interior of housing 72

is enlarged near the diaphragm 73 to support a spring 75 which is adapted to abut the head of the stem 74 against the diaphragm 73 for normally holding said stem and valve thereon in open position away from a seat 76 in a connection 77 communicating with the housing. The left hand end of the stem 66 normally abuts the diaphragm 73.

The pipe 57 is connected to the housing 72 and communicates with the interior thereof above the seat 76.

The spring 68 is comparatively strong and it may be adjusted, by adjusting the guide member 65 which is threaded in the housing 64, to the pressure desired so that when the pressure on the steam side of the diaphragm 63 becomes too great the stem 66 will move to abut the diaphragm 73 and act to close or partly close the valve 74 to cut off the steam to the pipe 28 and the burner.

Secured on the stem 66 is a stop member 78 which is adapted to actuate an arm 79 about a pivot 80 on the support 70 in accordance with the movement of said stem. The upper end of the arm 79 is forked to contact with a pin 81 secured on a disk 82 which is adapted to oscillate about a fixed cylindrical member 83 having a notch 84 in its left hand periphery.

A pair of contactors 85 and 86 are secured on the disk 82 and are adapted to oscillate therewith. The contactors 85 and 86 have electrically connected thereto binding posts 87 and 88 respectively. The contactor 85 is pivoted on the disk 82 at the point 89 and is spring impelled about said pivot point against the periphery of the member 83. A roller 90 rotatable about a pin 91 in the contactor 85 is adapted to ride on the periphery of the member 83 and to move out of the notch 84 in said periphery when the disk 82 has been rotated sufficiently. When the roller 90 moves out of the notch 84, contact points 92 on the contactors 85 and 86 will separate for cutting out the spark plugs and gasoline supply, as will be described hereinafter. When the stem 66 moves to the right as will be the case when the steam pressure is low and the disk 82 will be moved in a clockwise direction causing the roller 90 to drop again into the notch 84 resulting in the gasoline supply and spark plug being again operated as will also be described hereinafter.

Electric control mechanism.

By reference to Fig. 9 will be seen the electric connections of the various mechanisms for the purpose of controlling the same and the operation of the plant.

A battery 93 has its positive terminal connected to the arm 96 of a hand switch 95, which is preferably secured on the dash board, and the negative terminal connected to the binding post 88 of the automatic steam switch. The latter terminal of the battery 130

is also connected to the negative terminal of the blower (motor) 31. The arm 96 is adapted to be contacted with contact points 97, 98 and 99 on the switch 95, said arm being wide enough to contact with two of said points at once if desired. The point 97 is connected to the positive terminal of the blower 31. The point 98 is connected to the positive terminals of the spark coil 33 and the solenoid 35. An ammeter 94 is inserted in the line between the positive terminal of the battery and the switch 95 to show the current flowing in the circuit. The negative terminals of the spark coil 33 and the solenoid 35 are connected to the binding post 87 of the steam controlled switch. It is to be borne in mind that the binding posts 87 and 88 are connected together when the pressure is low in the boiler and on starting up.

10 *The operation is as follows*—When it is desired to start the plant up the arm 96 is moved to cover the points 97 and 98 thereby energizing the blower (motor) 31, the solenoid 35 and the spark coil 33 causing the 15 gasolene valve 48 (Figure II) to admit gasoline to the burner and the spark plugs 32 to ignite the same. The blower 31 will furnish the necessary air for complete combustion so that a hot flame is directed across the 20 nozzle 21 into the fire box where it is swirled upward by means of the previously described shape of the fire box 18. When the steam has formed in the boiler the fuel valve 26 (Figure VIII) is opened to admit fuel oil 25 to the tube 25 of the burner and the valve 55 (Figure VI) is opened to admit steam through the pipe 57 and valve 74 to the chamber 22 of the burner where it rushes out the aperture 23 and the nozzle 21 drawing the 30 fuel oil from the tube 25 and atomizing it as it leaves the nozzle. When the atomized oil and steam strikes the gasoline flame and the spark plugs it ignites. It is a characteristic of this burner that the fuel valve may 35 be set in open adjustment and thereafter the admission of steam will govern the flow of oil and the heat of the flame.

The switch arm 96 may then be moved off of the point 97 to cut out the blower (motor). 0 When sufficient head of steam has been obtained the stem 66 (Figure VI) will be moved to the left by the steam pressure on the diaphragm 63 which will cause the separation of the contact points 92 electrically disconnecting the posts 87 and 88 (Figure IX) and cutting out the spark coil and the solenoid 35, thus shutting off the spark and the gasoline to the burner. The movement of the stem 66 to the left due to excessive pressure will also retard the flow of steam through the valve 74 to the burner thus decreasing the flame. If later, the pressure drops, the stem 66 will again move to the right opening the valve 74 further and increasing the flow of steam to the burner, increasing the

flame, which tends to restore the pressure. If the arm 96 (Figure IX) is left in position over the contacts 97 and 98 and the pressure drops sufficiently so that the stem 66 moves far enough back again to the right the contact points 92 (Figure VI) will again close cutting in the gasoline, and spark plugs, starting up the gasoline flame to aid the primary fuel oil flame.

10 It is thus seen that the pressure in the boiler is automatically kept up.

It will also be seen that the steam may be quickly raised by the use of the auxiliary heating means in the burner.

15 It will also be seen that the plant is compact and that the water tube boiler in combination with this type of fire box and burner gives high evaporating power so that the power per unit space is unusually high.

It will also be seen that due to the arrangement of tubes in the boiler, a high convection is obtained giving a maximum circulation and heat transfer and that superheated steam is delivered to the engine reducing the loss in economy from condensation.

20 It is also evident that the installation is simple and economical of manufacture and upkeep.

25 It is further apparent that the arrangement of tubes and connections is such as to take care of expansion and contraction due to rapid changes in temperature.

30 It will be also evident that the parts are easily accessible for inspection, renewal or repair.

35 By the provision of the spring pressed closure on the boiler casing damage from excessive pressure within is eliminated.

40 It is also to be noted that by providing the particular form of fire box the fuel from the burner is given a double whirling motion which results in practically complete combustion within the fire box and boiler giving off a maximum number of B. t. u.'s per gallon of fuel and wasting a very small percentage 45 out of the stack. Thus the highest economy is obtained.

45 By providing the diaphragm type of valve, leakage of gasoline and steam is eliminated.

50 I am aware that many changes may be made and numerous details of construction may be varied through a wide range without departing from the principles of this invention and I therefore do not purpose limiting the patent granted hereon, otherwise than necessitated by the prior art.

55 I claim:

1. In a power plant, a series of vertically spaced generating coils, each having a plurality of convolutions in a horizontal plane, a pair of headers outside the series of coils and to which the opposite ends of the coils are connected at vertically spaced points along the headers, a preheating coil above the series of generating coils having a discharge pipe de- 60

pending into one of the headers, a storage coil surrounding the series of generating coils in spaced relation and in connection at one end with the upper end of the other header, and a superheating coil below the series of generating coils and in connection with the other end of the storage coil. 15

2. In a power plant, a series of vertically spaced horizontally spiral generating coils, a 10 pair of headers outside the said coils, and to which the coils are connected at their ends at vertically spaced points along the headers,

a preheating coil discharging into one of said headers, a helical storage coil surrounding the several generating coils in spaced relation and connected at its lower end to the upper end of the other header, and a horizontally spiral superheating coil below the series of generating coils and connected at one end to the upper end of the said storage coil. 20

In testimony whereof I have hereunto subscribed my name.

FREDERICK A. TRINKLE.
